MEANS FOR RETARDING CINDER CUTTING

Walter B. Leaf, Denver, Colo.

Application March 2, 1943, Serial No. 477,778

5 Claims. (Cl. 110—87)

1

This invention relates to means for retarding cinder cutting in fire boxes and more specifically, in the fire boxes of steam locomotives.

In many locomotive designs, the fire box is divided into upper and lower combustion zones by an arch member causing the rising gases to flow first in one direction until the end of the arch is reached and then turn and flow in a reverse direction until the gases pass into the flues in the boiler tube zone.

In such a movement, the gases reach high velocities and assume definite courses of travel so spaced as to create areas of partial vacuum, which induce a circulatory movement of the high velocity gases into such spaces. As a consequence of this action, the lower flues of the boilers do not receive their proportionate share of the gases of combustion and become plugged with cinders in a relatively short time.

Likewise, the uneven distribution of the gases of combustion causes cinder cutting of tubes, superheater units, flue sheets and crown flues, bolt heads in the areas where the high velocity gases contact such members. Particularly, at the end of the arch, the gases whip rapidly around and travel in the opposite direction in a space limited to from one-third to one-half of the total space between the arch and the crown sheet.

It is an object of the present invention to provide a simple, economical and efficient means for directing and controlling the flow of gases in a fire box to obtain a more efficient distribution of such gases.

A further object of the invention is to provide a simple, economical and efficient means for reducing the velocity of gases of combustion in a fire box.

Other objects reside in novel details of construction, and novel combinations and arrangements of parts, the details of which will be described in the course of the following description.

To afford a better understanding of the invention, reference is made to the accompanying drawings illustrating typical embodiments of the invention. In the drawings, in the several views of which like parts have been designated similarly,

Figure 1 is a fragmentary, central section through the fire box of a locomotive boiler, embodying features of the present invention;

Figure 2 is a section taken along the lines 2—2,

Figure 1;

Figure 3 is a fragmentary, central section through the fire box of a locomotive boiler, em-

bodying other features of the present invention; and

Figure 4 is a section taken along the line 4—4, Figure 3.

Referring first to the form of the invention illustrated in Figures 1 and 2, the fire box 5 is of conventional design having an end wall 6 and a crown sheet 7 of conventional size and shape. The lower portion of the fire box is enclosed by a grate section 8 bordered by a Gaines wall 9, while at its end opposite the end wall 6 a flue sheet 10 is disposed to receive the gases of combustion passing out of the fire box 5. A throat sheet 12 of the usual type is positioned below the flue sheet 10.

A siphon member 13 of the dual tube type extends from the throat sheet 12 into and through fire box 5, being supported from crown sheet 7 at its upper extremity and by the Gaines wall 9 and throat sheet 12 at its lower extremity.

An arch member designated generally by reference numeral 14 and comprising an interconnected series of fire brick 14a supported on lugs 15 mounted on siphon tubes 13 and side sheets 16, extends from Gaines wall 9 at an inclination through fire box 5 for a substantial distance and divides the fire box into upper and lower combustion zones designated A and B respectively.

The construction thus far described is conventional in locomotive boilers and comprises a part of the present invention, only to the extent that such parts are utilized with other features hereinafter to be described.

To eliminate the detrimental effects of the uneven distribution of the gases of combustion induced by the arrangement of arch 14, a deflector arch member designated by the reference numeral 17 is disposed in overhanging relation to the upper end of arch 14.

Arch 17 is composed of a series of interconnected fire brick 17a supported from siphons 13 and side sheets 16 on lugs 15. Preferably the arch 17 should be so shaped that its inner end is approximately on the line bisecting the angle between the crown sheet 7 and arch 14, while its outer end is curved to approximately conform to the normal gas flow about arch 14.

In this form of the invention, the tiles 14a at the end of the arch 14 underhanging arch 17 have their upper surfaces curved to substantially conform to the curvature of the under surface of arch 17 and thus provide a passage 18 of substantially uniform width.

It will be observed by reference to Figure 1 that the deflector arch 17 overlaps arch 14 for about

three-fourths the length of arch 17. This arrangement prevents the hot gases entering passage 18 from rising toward crown sheet 7 and directs them instead along linear courses against a substantial portion of the surface of flue sheet 10. At the same time other gases traveling through the space between deflector arch 17 and crown sheet 7 also assume a substantially linear component parallel to the surface of crown sheet 7 until they reach the surface of flue sheet 10 against which gases passing through passage 18 do not penetrate.

Referring to Figure 1, it will be noted that three zones have been designated in grate section 8. Gases of combustion rising from zone x travel upwardly into the space between deflector arch 17 and crown sheet 7. The gases rising from grate section y travel into passage 18, while the gases rising from section z flow directly to a passage 19 in Gaines wall 9. Preferably, the clearance between deflector arch 17 and crown sheet 7 is sufficient to provide a gas velocity somewhat less than the calculated gas velocity through passage 18.

As a consequence of this arrangement, a uniform distribution of gases is attained with a close control of the velocity of such gases as well. The gases passing above deflector arch 17 are required to engage a smaller surface area on flue sheet 10 than the gases passing through passage 18, and by having the velocity of the gases in passage 18 somewhat in excess of the velocity in said other zone, a uniform distribution results.

This arrangement prevents the development of excessively high velocities in the travel of the gases about the end of main arch 14 by its division of such gases, forcing a substantial portion thereof to assume a downward component by reason of the shape and location of the under surface of deflector arch 17 before they have traveled any appreciable distance in the direction of flue sheet 10. As a consequence, cinder cutting of tubes and flues, superheater units, flue sheets and crown bolt heads is substantially reduced and the engines steam much better, thus reducing fuel consumption and increasing boiler efficiency. Further, by utilizing substantially the entire available space in the reverse movement of the gases, formation of a partial vacuum condition is eliminated and velocities are substantially reduced.

The form of the invention illustrated in Figures 3 and 4 employs the same principles of operation and is generally similar in structural arrangement to the form of the invention illustrated in Figure 1. To this end, the fire box 5 has the usual end wall 6, crown sheet 7, side sheets 16 and grate section 8, enclosed at one end by a flue sheet 10 under which is provided the usual throat sheet 12.

A dual type siphon member 13 is supported from crown sheet 7 at its upper end and from Gaines wall 9 and throat sheet 12 at its lower end. A main arch 14 extends from Gaines wall 9 upwardly at an inclination and the fire bricks 14a of this arch are supported from siphons 13 and side sheets 16 by supporting lugs 15 as clearly shown in Figure 4. Crown sheet 7, end plate 6 and side sheets 16 are enclosed by an outer shell member 20 and defines therewith fluid-circulating passages into which the upper ends of siphon members 13 open, as indicated at 21 in Figure 4.

A deflector member 17x in this form of the invention is supported in overhanging relation to the upper end of main arch 14, and in length, spacing and general arrangement is similar to

the arch 17 of Figure 1. The essential difference between the arches 17 and 17x resides in the composition of the arch 17x. This member is a hollow metallic body having openings to its hollow interior 22 connecting with siphon tubes 13 and the outer enclosure formed by shell 20. A heat transfer fluid circulates through the siphon tubes 13 and hollow interior 22 of the arch member 17x thereby preventing excessive heating of the surfaces of the deflector arch 17x through contact with the gases of combustion.

In this form, the main arch 14 is not curved at its upper end adjoining passage 18a as in the form illustrated in Figure 1. However, the curvature of the under side of arch 17x is sufficient to impart the necessary directional components to the gases in passage 18a, with the result that uniformity of gas distribution is attained in this form of the invention as well. However, the curvature of the main arch is a preferred feature as some excessive wear on the end fire bricks of the arch may result from the irregular shape of said end with reference to the direction of movement of gases into passage 18a.

From the foregoing, it will be apparent that in either of the forms illustrated, the gases rising from the grate section are distributed before they assume directional components toward flue sheet 10 and, as a consequence, the velocity and direction of said gases is under control throughout the entire course of their reverse flow toward flue sheet 10.

The control thus exercised affords even distribution of gases of combustion against the exposed surface of flue sheet 10, resulting in higher boiler efficiency and reduced wear due to cinder cutting and plugging of the flues.

It will be understood that either of the forms of deflector arches 17 or 17x may be used with a main arch having either a curved end of the type shown in Figure 1, or a straight end of the type shown in Figure 3.

In the foregoing description, the main arch has been shown in both forms as associated with a siphon structure. However, in certain types of fire boxes arch tubes are used as the supporting medium for the main arch, while in others circulator tubes are utilized to provide the intermediate support for the main arch. In all such arrangements, the arch is substantially the same in arrangement as the arches shown in Figures 1 and 3 and functions in an identical manner to divide the fire boxes into upper and lower combustion zones.

Consequently, where the term "main arch" has been used in the description and claims, it is meant to cover any form of main arch now in use in the fire boxes of locomotive boilers and the deflector arch of the present invention will be disposed above and in overhanging relation to the upper end of any such arch to divide the gases of combustion in their turning movement and thereby control velocity and direction of such gases.

Changes and modifications may be availed of within the spirit and scope of the invention as defined in the hereunto appended claims.

What I claim and desire to secure by Letters Patent is:

1. In a fire box having a lower grate section, a flue sheet at its rear end, a crown sheet forming an upper closure for the fire box, a main arch inclined upwardly and forwardly from a rearward point of support adjacent the flue sheet to divide the space between the grate section and the crown sheet into upper and lower combustion zones, the

upper end of said arch terminating in a curved portion, and a deflector arch supported in overhanging relation to said main arch with a portion extending forwardly beyond the end of the main arch to divide the gases of combustion rising from said grate section prior to their passage between the main arch and the crown sheet, the underside of said deflector arch being substantially concentric with the curved surface of the main arch to direct one portion of the divided gases directly to the flue sheet.

2. In a fire box having a lower grate section, a flue sheet at its rear end, a crown sheet forming an upper closure for the fire box, a main arch inclined upwardly and forwardly from a rearward point of support adjacent the flue sheet to divide the space between the grate section and the crown sheet into upper and lower combustion zones, the upper end of said arch terminating in a curved portion, and a deflector arch of curved section concentric with the curvature of the main arch supported in overhanging relation to said main arch with a portion extending forwardly beyond the end of the main arch to divide the gases of combustion rising from said grate section prior to their passage between the main arch and the crown sheet and directing the divided gases directly to the flue sheet.

3. In a fire box having a lower grate section, a flue sheet at its rear end, a crown sheet forming an upper closure for the fire box, a main arch inclined upwardly and forwardly from a rearward point of support adjacent the flue sheet to divide the space between the grate section and the crown sheet into upper and lower combustion zones, the upper end of said arch terminating in a curved portion, and a deflector arch supported in overhanging relation to said main arch with a portion extending forwardly beyond the end of the main arch to divide the gases of combustion rising from said grate section prior to their passage between the main arch and the crown sheet, the upper and lower surfaces of said deflector arch being substantially concentric with the curved surface of the main arch to direct each

portion of the divided gases directly to the flue sheet.

4. In a fire box having a lower grate section, a flue sheet at its rear end, a crown sheet forming an upper closure for the fire box, a main arch inclined upwardly and forwardly from a rear point of support adjacent the flue sheet and extending in undulating arrangement laterally of the fire box to bridge the same and divide its space into upper and lower combustion zones, and a deflector arch supported in overhanging relation to said main arch with a portion extending forwardly beyond the end of the main arch to divide the gases of combustion rising from said grate section prior to their passage between the main arch and the crown sheet, the surface of the deflector arch nearest the main arch being arranged in substantially parallel relation to said undulating contour of the main arch to cause the gases traveling between said surfaces to travel at substantially uniform velocity throughout the width of the fire box.

5. In a fire box having a lower grate section, a flue sheet at its rear end, a crown sheet forming an upper closure for the fire box, a main arch inclined upwardly and forwardly from a rearward point of support adjacent the flue sheet to divide the space between the grate section and the crown sheet into upper and lower combustion zones, the upper end of said arch terminating in a curved portion, siphon tubes extending longitudinally in said upper combustion zone, and a deflector arch comprising a hollow, fluid-containing body supported in overhanging relation to said main arch with a portion extending forwardly beyond the end of the main arch to divide the gases of combustion rising from said grate section prior to their passage between the main arch and the crown sheet, the hollow interior of said deflector arch being in conductive connection with said siphon tubes in the fire box for circulating a heat-transfer liquid through the deflector arch.

WALTER B. LEAF.
